DESIGN FOR A LAMP OR SIMILAR ARTICLE

Lawrence J. Gagnon, Bay Village, Ohio, assignor to J. Schrader Company, a partnership composed of J. Schrader and Lawrence J. Gagnon

Application September 11, 1947, Serial No. 141,328

Term of patent 3½ years

(Cl. D48—20)

To all whom it may concern:

Be it known that I, Lawrence J. Gagnon, a citizen of the United States and a resident of Bay Village, in the county of Cuyahoga and State of Ohio, have invented a new, original, and ornamental Design for a Lamp or Similar Article, of which the following is a specification, reference being had to the accompanying drawing, forming a part thereof.

In said drawing, Fig. 1 is a front elevational view of a lamp or similar article, showing my new design; Fig. 2 is a cross-sectional view on the line 2—2, Fig. 1; and Fig. 3 is a cross-sectional view on the line 3—3, Fig. 1. The dominant features of the design reside in those portions thereof which are shown in full lines.

I claim:

The ornamental design for a lamp or similar article, substantially as shown and described.

LAWRENCE J. GAGNON.
